CLAIM

The ornamental design for a two piece window tint meter, as shown and described.

DESCRIPTION

FIG. 1 is a left front perspective view of the light source and light meter units of a two piece window tint meter showing our new design;

FIG. 2 is a right rear perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 shows the light source unit in an operative relationship with the light meter unit, the broken line showing environmental structure only and forms no part the design.
